 a corporation of Pennsylvania

Application July 31, 1946, Serial No. 687,264

2 Claims. (Cl. 158—116)

1

My invention relates to burners, and more particularly to burners of the type having a substantially closed combustion space in which practically complete combustion of a combustible gaseous mixture is accomplished and from which heated products of combustion are discharged through a restricted outlet in the form of a high temperature gas stream.

Burners of this type usually are provided with an outer metal shell or housing in which is disposed a hollow refractory body whose cavity forms the substantially closed combustion space. The metal housing is formed with an opening through which the restricted outlet end of the refractory body projects, so that the high temperature gases issuing from the restricted outlet will not come in contact with the metal housing.

In many heating applications the metal shells or housings are provided with brackets for mounting the burners in suitable fixtures of a machine. In addition to mounting the burner shells or housings in definite positions on machines in this manner, it is often necessary to locate the refractory bodies accurately within the metal shells or housings. This is particularly true when the burners are formed with elongated narrow slots which must assume definite positions with respect to work adapted to move into the high temperature gas streams at regions closely adjacent to the restricted outlets of the burners.

It is an object of the invention to provide an improvement in burners of the above type whereby the restricted outlet end of the burner can be accurately positioned within the outer metal shell or housing without the use of a jig or similar mechanism, thereby simplifying and reducing the cost of manufacture of the burners. I accomplish this by providing an outer metal shell and refractory body therefor which are formed in such a manner that the restricted outlet end of the body can be accurately positioned within the shell and precisely locate the position of the restricted outlet with respect to the shell.

The above and other objects and advantages of the invention will be more fully understood upon reference to the following description and accompanying drawing forming a part of this specification, and of which Fig. 1 is a vertical sectional view of a burner embodying the invention; Fig. 2 is an end view, partly broken away and in section, looking toward the restricted outlet or discharge orifice of the burner illustrated in Fig. 1; Fig. 3 is an end view similar to Fig. 2 which shows only the restricted narrow open end of the outer shell, the refractory hollow body be-

2

ing omitted to illustrate the invention more clearly; and Fig. 4 is a fragmentary vertical sectional view similar to Fig. 1 illustrating the restricted outlet end of the refractory body being accurately positioned within the outer metallic shell.

Referring to the drawing, the gas burner embodying the invention includes a ring-shaped base member 11 formed to provide an inlet chamber 12 having a threaded opening 14 which is adapted to be connected to a suitable source of supply of a combustible gaseous mixture. The base member 11 is formed with an inwardly extending shoulder 15 at the top part of the inlet chamber 12 to receive the lower flanged end 16 of a circular burner screen 17 having a plurality of small apertures 18 extending therethrough.

At the top face of the base member 11 is secured a ring-shaped clamping plate 19, as by screws 20, for example, the inner edge of which overlies the flanged end 16 of the burner screen 17. In order to obtain a gas-tight seal about the burner screen 17, a gasket 21 of suitable material, such as asbestos, for example, is interposed between the plate 19 and base member 11.

The large open end of a cup-shaped metal shell or outer casing 22 is removably secured at 23 to the base member 11. Within the metal shell 22 is provided a hollow body having a cavity forming a combustion space 24 terminating at its upper end in a slotted discharge orifice or restricted outlet 25.

In the embodiment of the invention illustrated the hollow body comprises a number of parts or members of high temperature refractory material including a hollow body or annular member 26 which snugly fits about the upper reduced portion of the burner screen 17 and extends above the top surface of the latter to form a short passage 27 at the inlet end of the combustion space 24.

About the hollow body 26 is disposed the lower end of a hollow cylindrical member 28 which bears against the clamping plate 19 and extends upwardly therefrom alongside of the metal shell 22 to the sloping or tapered upper end of the shell. Within the member 28 and forming therewith a part of the refractory wall of the space 24 is disposed a hollow cylindrical member 29. The lower end of the member 29 bears against the top surface of the hollow member 26, and the upper end thereof bears against the larger end of an annular member 30 which forms the discharge or outlet end of the combustion space 24. The annular member 30, which projects through the small open end of the outer shell 22, bears against

the sloping or tapered part of the shell and at the extreme upper end is provided with a slot forming the restricted outlet 25 for the combustion space 24.

In order to withstand the high temperatures produced in the combustion space 24 during operation of the burner, the hollow member 26, inner cylindrical member 29 and upper annular member 30 may be formed of a suitable refractory material, such as beryllium oxide, for example, having high resistance to thermal shock and possessing rigidity and strength at high temperatures. The outer cylindrical member 28 is preferably formed of a refractory material, such as aluminum oxide, for example, possessing good insulating properties and having adequate strength to serve as the outer portion of the refractory wall. Although not to be limited thereto, the burner screen 17 may be formed of a refractory material, such as aluminum oxide, for example.

The refractory wall parts just described may be secured to one another and within the outer shell 22 by a suitable high temperature air-hardening cement, as indicated at 31, 32, 33 and 34, respectively. Such a high temperature cement upon hardening provides a rigid and unitary burner structure in which all of the refractory wall parts are effectively united to form the combustion space 24.

To operate the burner 10 to produce a high velocity gas stream of heated products of combustion, a combustible fuel mixture comprising a gaseous fuel and a combustion supporting gas is supplied through the inlet 14 from a suitable source of supply. When the burner 10 is relatively cool and at a low temperature, the gaseous mixture supplied thereto passes through the inlet chamber 12, burner screen 17 and space 24 from which it is discharged through the restricted outlet 25. The combustible gaseous mixture is initially supplied to the burner 10 at a relatively low pressure which may be equivalent to a pressure corresponding to about 5 or 6 inches of water column, for example, so that the gaseous mixture discharged from the space 24 can be ignited to produce and maintain a flame at the outlet 25.

When a flame is being maintained at the outlet 25, the pressure of the gaseous mixture supplied to the burner 10 may be momentarily reduced sufficiently to cause the flame to backfire through the outlet 25 onto the burner screen 17 in space 24. When this occurs a plurality of flames are produced and maintained at the upper ends of the small apertures 18.

When the flames are being maintained within the space 24 at the top surface of the burner screen 17, the pressure of the gaseous mixture supplied to the burner 10 may then be increased. After a short interval of time the flames maintained at the top surface of the burner screen 17 effect such heating of the inner refractory lining that these surfaces are heated to a high incandescent temperature. The heating of the inner refractory lining to a highly incandescent condition and radiant heat therefrom promotes substantially complete combustion of the gaseous mixture in the combustion space 24 before the mixture reaches the outlet 25. From the outlet 25 is discharged a high velocity jet or stream of heated gases at a temperature nearly equal to the temperature in the combustion space 24 and consisting substantially entirely of heated products of combustion.

During normal operation the burner 10 is char-

acterized by the absence of a bright and luminous flame. It is only when the burner is first started that a flame is momentarily maintained at the elongated slot or outlet 25, as previously explained. After the gaseous mixture has once been ignited, the delivery pressure of the mixture is reduced sufficiently to cause backfiring into the combustion space 24, so that burning of the gaseous mixture will take place at the top surface of the burner screen 17.

In a burner of the type just described, the heated products of combustion are discharged from the combustion space 24 through the restricted outlet 25 at an elevated temperature ranging from 2700° F. to 2900° F. and higher when a combustible gaseous mixture of air and ordinary gas, such as city gas having a B. t. u. rating of about 550 B. t. u. per cubic foot, for example, is supplied at a pressure in the neighborhood of three pounds per square inch. Under such operating conditions the pressure in the combustion space 24 may be equivalent to a pressure corresponding from 55 to 70 inches of water column and appreciably above that of atmospheric pressure. The heated gases are discharged from the burner at an average velocity of about 750 feet or more per second and at a maximum velocity of about 1000 feet or more per second.

30 Burners like the burner 10 just described are often employed in machines or heating equipment including provisions for moving and guiding into the high temperature gas streams work to be heated. In such case each metal shell 22 may be provided with a bracket 35 which is formed integrally therewith. The bracket 35 may comprise spaced apart arms having aligned apertures 36 therein adapted to receive a pin for pivotally mounting the burner on a suitable support or fixture to position the burner with respect to the work to be heated. To facilitate adjustment of the burner about its pivotal support, a part 37 may be removably secured at 38 to the bracket 35, such part being acted upon in any suitable manner to move the burner about its pivotal support and hence adjust the burner to its work heating position.

35 In the burner shown and just described, the restricted outlet 25 is formed as a narrow elongated slot. In many heating applications such slot must assume a definite position within the shell 22, so that the slot will be properly located with respect to the work adapted to move into the high temperature gas stream. In accordance with the present invention, in order to position the restricted outlet end of the refractory body accurately within the shell 22, the shell at the narrow open end thereof is provided with a pair of spaced apart locating elements or pins 39.

40 The narrow open end of the shell 22 is formed with shoulders or bosses 40 having openings therein to receive the ends of the pins 39. The ends of the pins 39 are firmly anchored in position at the narrow end of the shell 22, as by a press-fit, for example. As best shown in Figs. 2 and 3, the pins 39 are parallel to one another and extend across the ring-shaped end opening in the shell 22 through which the annular member 30 of the refractory body projects.

45 The annular member 30 is formed with a pair of elongated straight shoulders 41 which are spaced apart substantially the same distance as the pins 39. The straight side portions 42 of the refractory member 30 adjacent to the shoulders 41 fit snugly between the pins 39, and, when the refractory body is snugly disposed within

the shell 22, the shoulders 41 bear directly against the pins 39 so that the refractory body and restricted outlet 25 will be accurately positioned within the shell 22. With this arrangement the elongated restricted outlet 25 is not only positioned angularly with respect to the shell 22 and bracket 35 thereon but also in a plane transverse to the longitudinal axis of the burner.

The burner 10 is fabricated by initially uniting the refractory members 26, 28, 29 and 30 together by suitable high temperature air-hardening cement, as explained above, to form the unitary hollow refractory body. After the refractory body is formed in this manner, I apply the air-hardening cement in paste form to the inner wall surface of the metal shell 22. After the interior surface of the metal shell is coated with cement, I then slidingly move the refractory body into the shell so that the restricted outlet end thereof passes between the pins 39, as shown most clearly in Fig. 4. The sloping exterior surfaces 43 of the annular member 30 serve to guide the refractory body between the pins 39 to bring the straight side portions 42 snugly between the spaced apart locating pins 39 to interlock the refractory body and shell 22. When the shoulders 41 engage the pins 39, excess cement flowing from both ends of the shell 22 is wiped, and thereafter the burner screen 17 and base member 11 and parts associated therewith are secured in position to hold the shoulders 41 against the pins 39.

In this construction it is not necessary to employ a jig or like mechanism to position the hollow refractory body within the outer metal shell 22. Since outer metal shells like the shell 22 often are cast shapes, it is desirable to provide a coating or layer of air-hardening cement at the inner surface of the metal shell to facilitate insertion of the refractory body within the shell and insure a tight fit of these parts. This is so because difficulty is encountered when a relatively tight sliding fit must be made directly between the roughened surfaces of a cast metal shell and a refractory body adapted to be positioned therein. It is highly desirable to position the hollow refractory part snugly within the outer shell 22 for the reason that the shell serves to hold the refractory body together even when cracking of the refractory walls occurs upon repeatedly heating the refractory body to high elevated temperatures.

It will thus be seen that I have provided an improved burner in which the outer shell and inner refractory hollow body are utilized to facilitate positioning the refractory body in a definite position with respect to the outer shell. Moreover, a simple fabricated construction is obtained in which the hollow refractory body can be readily replaced even in the field, when this

becomes necessary, without the use of special tools, thereby producing an inexpensive and easily manufactured construction.

Although I have illustrated and described a particular embodiment of my invention, I do not wish to be limited to the particular arrangement set forth, and I intend in the following claims to cover all modifications which do not depart from the spirit and scope of my invention.

10 What is claimed is:

1. A gas burner comprising a metal shell having an opening in a wall thereof, a hollow body in said shell which provides a substantially closed combustion chamber having an inlet for a combustible gaseous mixture and a restricted outlet for high temperature heating gases, said body being disposed in said shell so that the restricted outlet end of said body projects through and beyond said opening and high temperature heating gases adapted to issue from the restricted outlet avoid contacting said shell, said body at the restricted outlet end thereof having a pair of substantially straight shoulders in spaced apart parallel relationship at the exterior surface thereof, and a pair of spaced apart parallel pins fixed to said shell at said opening and extending across the latter, a portion of the restricted outlet end of said body extending into the space between said pins so that said shoulders engage and contact said pins to locate the restricted outlet in a definite position with respect to said shell.

2. A gas burner having a metallic shell provided with an opening in one end thereof and a bracket projecting from its outer surface, a hollow refractory structure forming a combustion chamber received by said shell, said structure being provided with an inlet for a fuel mixture at one end and an elongated outlet at the other end, said outlet extending through the opening in said shell, a pair of parallel locating pins mounted in said shell and extending across said opening, said pins being spaced far enough apart to receive said elongated outlet between them, and said structure being formed with surfaces to be engaged by said pins to locate said structure with respect to said shell whereby said elongated outlet will be located at a definite angular position with respect to said bracket.
